Specification for Design. Patented July 26, 1921.

Application filed March 5, 1921. Serial No. 450,092. Term of patent 14 years.

To all whom it may concern:

Be it known that I, WILLIAM A. PECK, a citizen of the United States, and resident of New Haven, in the county of New Haven and State of Connecticut, have invented a new, original, and ornamental Design for Nail-Sets, of which the following is a specification, reference being had to the accompanying drawing, forming part thereof.

In said drawing Figure 1 is an elevation

of a nail set showing my new design and Fig. 2 is a cross sectional view of the same taken on the line 2—2 of Fig. 1.

I claim—

The ornamental design for a nail set as shown.

Signed at New Haven, in the county of New Haven and State of Connecticut this 3rd day of March, A. D. 1921.

WILLIAM A. PECK.
